UNITED STATES PATENT OFFICE.

WILLIAM C. HUSS, OF CINCINNATI, OHIO.

DESIGN FOR A WALL-FIXTURE FOR COUNTERS.

SPECIFICATION forming part of Design No. 21,370, dated March 8, 1892.

Application filed January 2, 1892. Serial No. 416,904. Term of patent 3½ years.

To all whom it may concern:

Be it known that I, WILLIAM C. HUSS, a citizen of the United States, and a resident of Cincinnati, in the county of Hamilton and State of Ohio, have invented a certain new and useful Design for Bar-Fixtures, of which the following is a specification.

My invention consists in a new and original design for the back or wall fixture for a counter, the leading features of which are the end supporting-columns and the central column supporting the cornice, together forming alcoves or recesses between the columns; and it consists in the peculiar features shown in the accompanying drawings, in which—

Figure 1 is a front view of one side of the fixture and the central upright. Fig. 2 is a view partly in irregular vertical section and partly in elevation, which illustrates the effect produced when taken in connection with the following description of the drawings.

Referring to separate parts of the design, A is a rectangular column in cross-section, except the corners, which are slightly rounded off. This has an ornamental base a and carved capital a'. Upon the outer front edge of the column is an ornamental torch a². The bowl of the torch is open fret-work, within which is a globe a³. Upon top of the capital a' is mounted a cluster of four columns B, surmounted by a single ornamental capital b. There are two of these uprights—one at each end—to support the forwardly-projecting cornice C.

The case or closets D of the fixture are closed by doors which have panels b and a projecting top or shelf b'. The central portion of the base b² is sunk back of the side portions, and above this portion is placed a frame E, within which is the panel e. The angular recess in each front corner of this frame is fitted with a fluted column e', having a molded base and carved capital, which apparently support the molded top e² of the frame. The projecting front part of the frame is apparently supported by curved consoles e³. Upon top of the frame are five short

columns e⁴ in front and one in the rear of each end column, surmounted by a single carved cap e⁵. The space e⁶ back of the columns is a mirror, which reflects the front columns and gives the appearance of two rows of five columns. Upon top of the cap e⁵ and between it and the cornice is a capital F. This capital is formed by the carved abacus f, and the carved brackets f', curving upwardly and outwardly from the cap e⁵ to the cornice, which frame the curved plates f², which fit in the front and both sides. Round beads of the same material as the frame extend transversely across from bracket to bracket.

The cornice C is formed of the carved molding c, above which are a series of arches c', having bracket-shaped keystones extending down to the molding c, and between the arches are carved triangular panels c². These arches are capped by the upper molding c³ of the cornice, and upon top of it at each end are fluted paneled pilasters e⁴ at each end, a cap-molding c⁵ extending from one pilaster to the other, and is supported between the pilasters by short columns c⁶. The arched portion of the cornice extends down from the front of the cornice-cap c⁸, forming an angular space c⁷, Fig. 2, extending from end to end of the fixture. Within this space is fitted curved plates.

In the spaces between each of the end columns and central support are arranged mirrors G, having molded frames, end supporting-columns g, projecting cornice-molding g', and a carved scroll-work finial g². Above the inner columns of the glass-frame, back of and above this molded-frame cornice, are panels g³, of stucco or ornamental caisson pierre.

What I claim is—
The design for a wall-fixture for counters, substantially as herein shown and described.

WILLIAM C. HUSS.
